UNITED STATES PATENT OFFICE.

JOSEPH B. NEIL, OF FILBERT, SOUTH CAROLINA, ASSIGNOR TO SOUTH CAROLINA
COTTON PICKER COMPANY, OF YORKVILLE, SOUTH CAROLINA.

COTTON-PICKING MACHINE.

1,121,592.

Specification of Letters Patent. Patented Dec. 15, 1914.

Application filed February 8, 1912. Serial No. 876,426.

To all whom it may concern:

Be it known that I, JOSEPH B. NEIL, a citizen of the United States, residing at Filbert, in the county of York and State of 5 South Carolina, have invented a new and useful Cotton-Picking Machine, of which the following is a specification.

This invention relates to machines for 10 picking cotton and is more particularly an improvement upon the structure disclosed in Patent No. 856,178, issued to me on June 4, 1907.

One of the objects of the invention is to 15 provide a machine of this type adapted to be drawn along a row of cotton plants and to comb the plants, said machine including revoluble members designed to engage the cotton fibers and completely remove them 20 from the bolls, the picking elements being so arranged relative to each other as to both pick the cotton and convey it to the upper portion of the machine whereby the cotton is dumped on to a conveyer adapted to conduct it to suitable bagging mechanism.

25 A further object is to provide a machine of this character which will not choke and which is designed to separate the cotton fiber from the leaves and other undesirable materials while the fiber is being picked 30 from the plant and while it is being conveyed upwardly to the doffing elements.

A further object is to provide a picking machine which will act efficiently upon 35 plants of all sizes, means being provided whereby the picking elements will yield when subjected to certain resistances, the plants being thus protected from injury such as heretofore has resulted from crushing.

40 A further object is to provide picking mechanism the plant engaging elements of which are so mounted as to have the maximum up and down movement without coming into contact with each other.

45 A further object is to provide improved means for holding back the plants while the machine is combing through them so that the limbs of the plants will not be broken or torn off during the picking operation.

50 Another object is to provide simple means for holding the machine in proper position relative to the row while it is being drawn along said row.

With the foregoing and other objects in view which will appear as the description

proceeds, the invention resides in the combination and arrangement of parts and in the details of construction hereinafter described and claimed, it being understood that changes in the precise embodiment of the invention herein disclosed can be made 55 within the scope of what is claimed, without departing from the spirit of the invention.

In the accompanying drawings the preferred form of the invention has been shown.

In said drawings: Figure 1 is a side elevation 65 of the machine. Fig. 2 is a front elevation thereof. Fig. 3 is a vertical transverse section through a portion of the frame of the machine. Fig. 4 is an enlarged vertical transverse section through one of the 70 picking frames. Fig. 5 is an elevation of a portion of the working face of one of the frames. Fig. 6 is a front elevation of one of the frames and showing the means employed for transmitting motion to the various picking rolls and holding rolls. Fig. 7 is a reduced section on line A—B Fig. 4, 75 all of the rollers of the picking frames, together with their drive belts and pulleys being removed, and only the doffing brush 80 being shown. Fig. 8 is an enlarged transverse section through one of the picking rollers. Fig. 9 is a detail view of a portion of the picking surface of the roller. Fig. 10 is a side elevation of one of the conveyers and elevators. Fig. 11 is a perspective view of a portion of one of the guards 85 for the front ends of the picking frames. Fig. 12 is an enlarged view partly in section and partly in elevation of the bagging 90 mechanism.

Referring to the figures by characters of reference 1 designates an arched frame having sleeves 2 adjustably mounted on the side portions thereof and held against movement 95 relative to said portions by any suitable means, such as set screws 3 or the like. Spindles 4 extend laterally from these sleeves and are supported by wheels 5, one of these wheels having a drive sprocket 6 100 secured to it and revoluble therewith.

Arms 7 extend inwardly from the lower end of the frame 1 and have upstanding pivot studs 8 on their inner end portions disposed in alignment with pivot studs 9 105 extending downwardly from the upper or crown portion of the arched frame 1. Each pair of pivot studs 8 and 9 engages a swing-

ing frame 10 preferably made of angular metal, such as a T-iron, each frame consisting of a bottom strip 11 engaging the lower pivot stud 8 at a point between its ends, a rear upstanding strip 12 merging at its upper end into a forwardly extending horizontal strip 13 which extends under the top of the arched frame 1 and engages the pivot element 9, an upstanding portion 14 at the front end of the forwardly extending portion 13, said upstanding portion being provided, at its upper end, with a forwardly extending portion 15, and an elongated front strip 16 connecting said forwardly extending portion 15 to the front end of the bottom strip 11. The upper portion of the front strip 16 and the portions 14 and 15 of the frame constitute an upper frame extension indicated generally at 17. Thus it will be seen that two swinging frames are provided, said frames being mounted to swing about parallel axes.

Side strips 18 are fixedly connected to and extend rearwardly from the upper portion 25 of the arched frame 1 and are held rigid relative to the said arched frame by means of inclined braces 19. Each of these side strips has a downwardly extending L-shaped extension 20 also provided with a brace 21. Extensions 20 serve to support a platform 22, on which a bag, such as indicated at C, and which will be referred to hereinafter, may be placed.

A rod 23 is pivotally connected to each of 35 the portions 13 of the swinging frames 10 and extends inwardly therefrom, said rod slidably engaging a guide ear 24 depending from a cross member 25 mounted on the side strips 18. A spring 26 extends around each 40 rod 23 and bears at one end against the guide ear 24 and at its other end against a head 27 at the free end of the stem. Thus it will be seen that the springs 26 serve to push the heads 27 on the respective stems 23 45 toward each other and thereby cause the rear ends of the frames 10 normally to swing toward each other.

A motor 28 is mounted on the cross member 25 and is adapted to drive a chain 29 50 which, in turn, drives the sprocket 6 hereinbefore referred to. A standard 30 is supported above and moves with the side strips 18 and has a shaft 31 journaled therein and extending parallel with the sides of the machine. This shaft has a pulley 32 receiving motion from the motor 28 through a belt 33. The shaft 31 has a pulley 34 secured thereto in the plane of the axes of rotation of the frames 10 and this pulley is sufficiently broad to drive two oppositely extending belts 35 and 36. A shaft 37 is journaled in each extension frame 17 close to the top thereof and is provided, within said extension frame, with a sprocket 38. One end 65 of the shaft 37 projects rearwardly from the

extension frame and has a pulley 39 secured thereto. One of these pulleys 39 is adapted to be driven by the belt 35, which is crossed, while the other pulley 39 is adapted to be driven by the belt 36. Thus it will be seen 70 that the two shafts 37 will be simultaneously rotated in opposite directions. It is to be understood that pulleys 39 are located in vertical alinement with the pivot devices 8 and 9. Obviously, therefore, the frames 75 10 can be swung about their vertical axes without interfering with the transmission of motion from the shaft 31 to the pulleys 39 and shafts 37.

Supported by each of the swinging 80 frames 10 is a series of parallel horizontal tubular pivot members 40 arranged one above the other the rear ends of these pivot members being supported by the rear upstanding portions 12 of the frames 10 while the front end of each pivot member 40 is supported by a short shaft 41 journaled at one end within the front strip 16 and at its other end within an upstanding frame piece 42 mounted within the frame 10 and parallel with the front strip 16. A sprocket 43 is secured to each shaft 41 and the sprockets 43 in each frame 10 receive motion through a single chain 44, from the sprocket 38, idler sprockets 45 being interposed between the 95 sprockets 43 so as to hold the chain 44 positively in engagement with the teeth of the sprocket 43. A second sprocket 46 is secured to and rotates with each shaft 41.

Upwardly extending arms 47 are fixedly 100 mounted on each tubular pivot member 40 adjacent the ends thereof and are secured to the front and rear heads 48 and 49 respectively of a picking frame. These heads extend downwardly and inwardly at acute 105 angles to the arms 47 and are fixed relative to said arms. A shaft 50 is journaled in the upper ends of the heads 48 and 49 and has a sprocket 51 which receives motion, through a chain 52, from the sprocket 46 on shaft 41 110 thereunder. This shaft 50 carries a doffing brush 53 and also carries, adjacent its front end, two grooved pulleys 54 and 55 respectively. Shafts 56 are journaled in the heads 48 and 49 and are parallel with shaft 50, the 115 shafts 56 being arranged in staggered relation and each of them carrying a picking cylinder 57. Each of these cylinders is hollow and has a longitudinally corrugated working face or periphery, as will be apparent by referring to Fig. 8, and each corrugation has a longitudinally extending series of substantially V-shaped openings 58 extending transversely thereof, there being a spur or tooth 59 within each opening, all of the openings and teeth being arranged similarly within the cylinder. Thus it will be seen that any cotton fiber which may be forced within the concavities between the corrugations, will project into the openings 120 125 130

58 and be engaged by the points of the teeth 59.

5 Rollers 60 are journaled between the heads 48 and 49 and are disposed in staggered relation, each of these rollers being located at one side of one of the picking rollers 57. Certain of the rollers 60 project slightly above the upper inclined edges of the heads 48 and 49 while the other rollers 10 60 extend slightly below the lower inclined edges of the heads. Each of the rollers 60 has a wire 61 wrapped spirally therearound so as to form a worm the pitch of the wire being such as to feed toward the rear end 15 of the picking frame during the forward movement of the machine.

Each roller 60 has trunnions 62 extending from its ends, these trunnions bearing within heads 48 and 49. The trunnions 62 extending beyond the front head 48 have grooved pulleys 63 secured thereto. The shafts 56 project forward through the head 48 and together with shaft 50 have grooved pulleys 64 fastened thereto. An endless belt 65 engages the pulleys 64, said belt passing upwardly in engagement with the pulleys 63 of the rollers 60 located along the upper edges of the heads 48 and 49. Another endless belt 66 is mounted on one of the pulleys 30 64 and engages the pulleys 63 of the lower series of rollers 60. Idlers 67 may be suitably arranged so as to hold the belt taut and in proper engagement with the grooved pulleys 63.

35 It will be noted by referring to Fig. 6 that the pulleys 64 are of different diameters, the uppermost pulley being smaller than the pulley next thereunder and this arrangement being followed throughout the 40 series of pulleys 64. Obviously, therefore, the lower picking cylinder or roll 57 will rotate at a slower speed than the cylinder next above it and the third cylinder from the bottom will rotate even faster. It is preferred to have the cylinders 57 so geared that each one will rotate about twice as fast as the one next under it. All of the cylinders rotate in the direction indicated by arrows in Fig. 4. The rolls 60 all rotate at 45 the same speed and the worms formed by the wires 61 are designed to engage the plants acted on by the machine and to push the limbs rearwardly thus to compensate for the drag in a forward direction which is set 50 up by the machine while in engagement with the plants. Each of the pivot members 40 has an arm 68 connected by a spring 69 to adjustable bars 69' carried by the frames 10. Thus it will be seen that the spring pulls 55 constantly on the arm 68 and thus serves to yieldingly support the picking frame made up of the heads 48 and 49 and the parts connecting the same.

The front ends of the picking frames are 60 provided with shields 70 each of which is

preferably formed of sheet metal bent so as to prevent vegetation from coming into contact with the belts 65 and 66 and the pulleys driven thereby. All of these shields, with the exception of the lowermost ones are 70 similar in contour. The lower shields 71, however, are curved and extended forward so as to form lifting fingers whereby any fallen plants in the row being operated on will be elevated into position to be combed 75 by the picking rollers.

The outer side of each swinging frame 10 is provided with a housing 72 and within the bottom portion of this housing adjacent the front and back ends of the frame 10 are 80 rollers 73 and 74 respectively, additional rollers 75 and 76 being located within the housing slightly above and close to the roller 74. Another roller 77 is located in the housing adjacent the top of the rear portion 85 thereof. An endless conveyer belt 78 is mounted on the roller 73 and the upper run thereof extends over the roller 76 and under roller 75 and thence upwardly over roller 77 and downwardly under roller 74. Another 90 roller 79 is arranged within the housing close to and above the rollers 75 and 76 and is engaged by the lower portion of an endless belt 80, the upper portion of this belt being extended slightly above the roller 77 95 and being mounted on a roller 81. The upwardly extending portion of the belt 78 has one of its runs normally in contact with one of the runs of the belt 80 so that these two runs coöperate to grip any cotton which 100 may be supplied between the belts and to convey the cotton upwardly. It is to be understood that any cotton doffed from the picking rollers in the manner hereinafter set forth, will drop onto the upper run of 105 the lower portion of belt 78 and will be conveyed under the lower end of belt 80 and against the upwardly moving run of the belt 78 which will, in turn, carry it into position between said run and the belt 80. 110

Thus the cotton will be carried upwardly as hereinafter set forth and will be discharged over the upper roller 77. Spouts 82 are arranged to receive cotton discharged from the conveyer belts 80 and 78 and serve 115 to direct the cotton into a hopper 83 which is supported above the platform 22. The bottom of this hopper is formed of two opposed sections 84 and 85 having side wings which constantly lap. These sections are 120 held normally close together by means of one or more springs 86. A lever 87 is fulcrumed adjacent the hopper, preferably upon a bracket 88 extending from one of the side strips 18, and rods 89 extend from this lever 125 at opposite sides of its fulcrum and are connected to the respective hopper sections 84 and 85. Thus it will be seen that when the lever is swung in one direction, the two hopper sections will be moved apart against the 130

stress of springs 86, thereby permitting the contents of the hopper to fall therefrom, whereas, when the lever is released, springs 86 will return all of the parts to their normal positions.

Brackets 90 extend from the respective sections 84 and 85 close to the lower ends thereof and are adapted to be engaged loosely by the hooked ends 91 of arms 92, 10 these arms being pivotally connected, as shown at 93. The said arms are located in the mouth of a sack C and it will be understood that, by opening the sack to a slight extent the hooked ends 91 can be placed in 15 engagement with the brackets 90. When lever 87 is then shifted to open the hopper 83, the sections 84 and 85 will press against the hooked ends of the arms 92 and completely open the sack so that the material 20 within the hopper will be free to fall into the sack. As soon as the hopper is closed, the sack is partly closed and may then be easily removed from the hopper and a new sack placed in engagement therewith.

25 It will be understood from the description heretofore given that when the motor 28 is in operation, motion will be transmitted therefrom through the various belts and shafts, to the chains 44 and these chains 30 will cause the shafts 41 to rotate in unison. Motion will be transmitted from each shaft 41 to the pulleys and belts carried by the picking head associated with said shaft. As the corresponding heads on the opposed 35 swinging frames 10 converge rearwardly, as indicated in Fig. 2, it will be seen that, when the machine is propelled along a row of plants, the picking heads will pass under and over the branches of the plants and said 40 plants will thus be thoroughly combed. During this combing operation the picking rollers 57 and the holding rollers 60 are rotating. The teeth or spurs 59 on the picking rollers will engage the cotton fiber and pull 45 it out of the bolls, the rollers 60 located above the picking rolls serving to hold back the boll and preventing it from entering between the picking rollers. The fiber engaged by the lowermost roller 57 on each 50 picking head will be wrapped about said roller and conveyed up to a point where it will be engaged by the teeth or spurs on the next adjoining roller 57. As this last mentioned roller is traveling at a greater speed 55 than the roller thereunder, it will be seen that it has a greater capacity and is therefore capable not only of removing all of the cotton from the lower roll but also of picking cotton from the bolls contacted by said 60 second roll. From said second roll the cotton is passed to the third roll which likewise has a greater capacity than the second roll and this operation is continued throughout the height of the picking frame, 65 the cotton, upon its being engaged by the

teeth or prongs of the upper roll 57, being doffed by the brush 53 and thrown into the housing 72 and onto the conveyer belt 78. As the machine is moving forward during this picking operation, it will be apparent 70 that the rollers 57 will tend to pull the plants forward with the machine, thus either breaking or bending the plants to an undesirable extent. To offset this action, the rollers 60 have been provided 75 with the spirally disposed portions 61. These rollers operate to engage the plants and to push them rearwardly at the same speed as the machine is traveling forward so that, as a result, the limbs of the 80 plants will be combed away from the stems and the plants will be held substantially in their normal positions while being acted upon and there is thus no danger of mutilating them to an undesirable extent. As 85 the various picking frames are yieldingly supported by the springs 69, it will be seen that they will swing away from a plant or obstruction offering excessive resistance to their movement.

90 By shifting the bars 69' upwardly or downwardly the springs 69 can be caused to release or to pull downwardly on the arms 68, thereby shifting the picking frames downwardly or upwardly as desired 95 about the pivot members 40 to change their angles relative to the horizontal and to raise or lower the picking rolls. This adjustment is desirable especially when drawing the machine through the plants more than once. 100 As the pivot members are located at some distance below the upper ends of the picking frames, it will be seen that the movement of opposed frames toward each other during this tilting of the frames is reduced 105 to the minimum.

Any suitable means may be provided for shifting the bars 69'. As shown in Fig. 1, a lever 94 is preferably mounted on each frame 10 and is pivotally connected at one 110 end to the upper end of bar 69'. This lever carries a spring pressed pawl 95 which is designed to engage a toothed segment 96 whereby the lever may be locked in any position to which it may be moved. A handle 115 97 is fixedly connected to one of the frame extensions 20 and by means thereof the operator, who walks back of the machine while it is being propelled forward, can swing the machine laterally so as to properly guide it 120 along the row being acted on.

125 Any suitable mechanism may be utilized for driving the conveying and elevating belts. As shown in Fig. 1 a pulley 98 may be driven by the motor 28, this pulley transmitting motion, through a belt 99, to a pulley 100 which is secured to the shaft of the roller 81. A gear 101 is secured to the shaft of the roller 77 and is adapted to be driven by another gear 102 which rotates with the 130

pulley 100. As hereinbefore pointed out, the springs 26 serve to draw the rear ends of the picking heads toward each other by pulling on the rear ends of the frames 10 and thus, after the said frames 10 and the parts carried thereby have been spread apart by plants or the like passing between them, they will be returned automatically to their initial positions.

10 Importance is attached to the particular form of picking roll or cylinder 57 employed. It has been found that, by using this type of roll only the fiber of the cotton will be engaged by the teeth or prongs 59 and any leaves or trash which it is not desired to elevate to the doffing brush, will not be engaged by the teeth but will be left on the plants or else will drop to the ground before passing through the conveyer. The 20 picking rolls of each picking frame will pass over certain of the branches of the plants and under other branches. Thus it will be seen that practically all of the cotton on the plant will be reached by one or 25 more of the rolls and removed from the plant.

What is claimed is:—

30 1. A cotton picker including diverging series of parallel combined picking and conveying elements, and means for rotating the respective elements at different speeds simultaneously whereby the cotton picked by one element is removed by an adjacent element.

35 2. A cotton picker including diverging series of substantially horizontal combined picking and conveying elements, and means for rotating the respective elements at different speeds simultaneously whereby the cotton picked by one element is removed by an adjacent element.

40 3. A cotton picker including diverging series of parallel combined picking and conveying elements, said series being arranged in pairs and said pairs being superposed, and means for rotating the respective elements of each series at different speeds simultaneously whereby the cotton picked by one element is removed by an adjacent element.

45 4. A cotton picker including oppositely disposed inclined series of combined picking and conveying elements, and means for rotating one of said elements to pick cotton and for rotating an adjacent element to remove said picked cotton from the picking element.

50 5. A cotton picker including oppositely disposed inclined series of combined picking and conveying elements, each of said series being mounted to swing laterally, and means for rotating the respective elements of each series at different speeds simultaneously whereby the cotton picked by one element 55 is removed by an adjacent element.

6. A cotton picker including oppositely disposed inclined series of combined picking and conveying elements, each of said series being mounted to swing laterally, means for yieldingly holding the series 70 against swinging movement, and means for rotating the respective elements of each series at different speeds simultaneously whereby the cotton picked by one element is removed by an adjacent element. 75

7. A cotton picker including upwardly diverging series of parallel revoluble elements, each element constituting a combined picking and conveying device, and means for rotating each of said elements at a 80 greater speed than the next adjoining element thereunder to remove the picked cotton therefrom.

8. A cotton picker including upwardly diverging series of parallel combined picking and conveying elements, means for rotating the respective elements of each series at different speeds simultaneously, whereby the cotton picked by one element is removed by an adjacent element, and means for doffing 90 material from the uppermost element of each series.

9. A cotton picker including upwardly diverging opposed series of substantially horizontal picking rolls, means for mounting the said series whereby they travel between the branches of cotton plants, the rolls of opposed series converging toward their rear ends, said rolls constituting means for gathering the plants between them. 95

10. A cotton picker including upwardly diverging series of parallel picking rolls, the rolls of each series being disposed in staggered relation, and means for rotating each of said rolls at a greater speed than 100 the next adjoining roll thereunder.

11. In a cotton picker a plurality of revoluble picking elements, each of said elements being revoluble at a speed greater than the next adjoining element thereunder. 110

12. In a cotton picker a plurality of superposed revoluble picking elements, means for rotating each of said elements at a greater speed than the next adjoining one thereunder, each of said elements constituting 115 means for removing from the next adjoining element thereunder the cotton contained thereon.

13. In a cotton picker, a picking frame mounted for movement between the branches of a plant, and a series of superposed rolls mounted for rotation within the frame, each roll constituting combined picking and conveying means, and means for driving each roll at a greater speed than the next adjoining roll thereunder to remove cotton therefrom. 120

14. In a cotton picker, a series of superposed picking frames and a plurality of combined picking and conveying rolls car- 125 130

ried by each frame, whereby the cotton picked by one roll is removed by an adjacent roll.

15. In a cotton picker, a picking frame, a picking roll mounted to rotate within the frame, a combined picking and conveying roll within the frame for removing fiber from the first named roll, and means for doffing fiber from the last named roll.
16. 16. In a cotton picker, a picking frame, a picking roll mounted for rotation within

the frame, a combined picking and conveying roll within the frame, means for doffing fiber from the last named roll, and a conveyer for receiving the doffed material.

In testimony that I claim the foregoing as my own, I have hereto affixed my signature in the presence of two witnesses.

JOSEPH B. NEIL.
